UNITED STATES PATENT OFFICE

HANS VOGT, OF BERLIN, GERMANY

SOUNDING CONDENSER

Application filed February 26, 1929, Serial No. 342,705, and in Germany May 16, 1928.

My invention relates to sounding condensers. In my copending application, Serial No. 306,158, dated September 15, 1928, there has been described and claimed 5 a sounding condenser whereof the diaphragm consists of a thin foil of a light metal or alloy of high elasticity and strength, the said metallic foil being kept under high tension in radial direction and 10 mounted between two stationary perforated capacity surfaces or condenser armatures so as to be free to oscillate within the gap between the two spaced capacity surfaces.

The object of the present invention is to 15 provide a sounding condenser of the indicated type which in some respects may be regarded simply as an improvement over the structure described in said previous application, and wherein the acoustic frequency range of the oscillatory or vibratile diaphragm is increased for the purpose of 20 reproducing both the sounds of highest pitch and the sounds of lowest pitch, in their natural timbre and with greater loudness and sonorousness than hitherto could be attained by loud-speaking appliances.

As a fact the efficiency of a sounding condenser depends upon the properties of the electrostatic field acting to excite the vibratile diaphragm, that is to say, the condenser is the more efficient the more uniform and stronger the electrostatic field is, and as the latter increases in accordance with the 30 square of the approach of the capacity surfaces or condenser armatures, the said surfaces obviously ought to be approached or spaced as close as possible without interfering with the greatest oscillating deflection or amplitude of the diaphragm. Evi-

dently the oscillating range or amplitude of the diaphragm is greatest at the centre thereof and gradually decreases towards the periphery thereof since the peripheral edge of the diaphragm is fixed and immovable. 40 Consequently in case of flat capacity surfaces arranged in parallelism so as to be equally spaced at the centre and at any other or peripheral points, the intensity or strength of the electrostatic field will gradually decrease towards the periphery of the

two surfaces due to the width of the gap required between the latter in order to allow of the central portion of the diaphragm to freely oscillate between the said 55 two surfaces.

According to the present invention the stationary or interconnected rigid capacity surfaces of the condenser are so shaped that when they are duly assembled, the gap or space therebetween is greatest in the vicinity of the aligned axes thereof or centrally and progressively decreases towards the peripheries thereof, or in other words, the capacity surfaces are shaped to form shallow shells of spherical or approximately 30 spherical configuration with their concavities opposite the two faces of the diaphragm sandwiched therebetween. Viewing the fact that the amplitude of the oscillating diaphragm will extend or amount to a fraction of a millimetre only, even at the centre or the point thereof where the amplitude is a maximum, it is obvious that the sphericity of the opposite surfaces of two capacity bodies will be extremely slight 70 75 only.

Another object of my invention is to provide means, such as screws, in the one capacity body or in both, and which are adapted, to force the centres of the fixed capacity bodies apart from each other so as to impart to the latter the required slight spherical or concave form. In this way it is possible to ascertain experimentally the 30 best suitable degree of sphericity or concavity in each individual condenser by adjusting the set screw or screws so as to ensure the best effect as regards sound and timbre.

With the above and other objects in view, reference is had to the following specification and drawings in which there are exhibited several examples or embodiments of the invention which are in no way intended as a limitation upon the scope of the subjoined claims, as it is to be clearly understood that variations and modifications which fairly fall within the true scope of said claims may be resorted to when found 90 95 100 expedient.

In the accompanying drawings forming a part of this specification and showing for exemplification preferred forms and manners in which the invention may be embodied and practised, but without limiting the claimed invention to such illustrative instances:

Figure 1 shows in front elevation a sounding condenser constructed in accordance with the present invention; Figure 2 is a view in vertical cross-section of the same; and Figures 3 and 4 are similar sectional views of modified forms of the condenser.

Referring to Figures 1 and 2, *a* and *a'* indicate the two stationary fixed capacity surfaces or condenser armatures and *b* denotes the vibratile diaphragm with its circular peripheral edge clamped between two clamping rings *c* so as to be stretched at high radial tension, the arrangement of the assembled parts being such that the diaphragm *b* occupies a position in the median plane of the free space or gap between, the inner or opposite faces of the two capacity bodies *a* and *a'*. In the centre of the capacity surface or body *a'* a threaded bore is provided for the reception of a screw *e* elongated at its inner end to form a pin passing through a central hole of the diaphragm and adapted to abut against the centre of the opposite capacity surface *a*, so that when the screw *e* is screwed down towards and against the capacity surface *a*, the same will cause the latter to bulge and form spherical cavities or calottes in opposition. It will be seen that thus the cross-sectional width of the gap in which the diaphragm is free to oscillate, is greatest at the centre of the diaphragm and decreases gradually towards the periphery of the latter. The diaphragm is caused to oscillate when excited by electrical alternating voltages, as described in detail in the prior application Serial No. 306, 158 herein referred to.

In the centre of the concave surface of the capacity body *a* there is provided a small disk *d* of insulating material for the purpose of preventing the pressure difference of the two surfaces *a* and *a'* from being balanced by the screw *e*. It goes without saying, however, that any other suitable means may be employed for the same purpose.

Instead of a screw such as *e* adapted to exert a buckling or bulging pressure on the two capacity surfaces, draw-screws may be employed as shown in the modifications illustrated in Figures 3 and 4. In Figure 3 the heads *g* and *g'* of the draw-screws *f* and *f'*, respectively, are embedded in bushings or sockets *h* and *h'*, respectively, supported by or integral with bridles *i* and *i'*, respectively, whereof the extremities engage and are firmly connected with the rims *k* and *k'* of the capacity bodies *a* and *a'*, respectively. The threaded ends of the screw shafts en-

gage in correspondingly threaded bores the aligned axes of which coincide with the centre of the diaphragm, so that on turning the screws *f* and *f'* in one direction the two opposite centres of the capacity surfaces *a* and *a'* will recede from the diaphragm and the capacity surfaces will thus be given the desired concavity.

In the modification shown in Figure 4 the heads or outer ends of the screws *f* and *f'* are supported by the protective grids *m* and *m'*, respectively, usually provided for the purpose of protecting the condenser from external disturbing influences, so that the heads of the screws abut against the said grids when the screws are turned in order to give the capacity surface the desired shallow concavity.

I have herein described and shown several practical constructions of my present improvements, but it will be apparent that the device, particularly the adjusting means, is susceptible of embodiment in various other alternative forms without departure from the invention whereof the chief features resides in the shallow bulged form or concavity of the two capacity surfaces or in the means provided for imparting to the latter a shallow bulged form or concavity whereof the radius of curvature is adjustable for the purpose of positioning the said two surfaces as close by the vibratile diaphragm as can be done without interfering with the oscillatory movements of the latter. I therefore, reserve the privilege of resorting to all such legitimate changes as may be fairly embodied within the spirit and scope of the invention as claimed.

What I claim is:—

1. A sounding condenser comprising two firmly interconnected capacity surfaces, a vibratile diaphragm disposed midway between the said two surfaces, and means for causing the said capacity surfaces to bulge in opposed directions with relation to each other so as to form shallow concavities with the diaphragm freely sandwiched therebetween.

2. A sounding condenser comprising two firmly interconnected capacity surfaces, a vibratile diaphragm disposed midway between the said two surfaces, a screw engaging with its threaded end in a threaded central bore of the one capacity surface, and abutting with its other end against the other capacity surface, and means for insulating the said screw with relation to the said other capacity surface, substantially as and for the purpose set forth.

In testimony whereof I affix my signature.

HANS VOGT.
